UNITED STATES PATENT OFFICE.

WILLIAM WILSON, OF BOSTON, MASSACHUSETTS, ASSIGNEE TO CAMPBELL BOSWORTH MACHINERY COMPANY, OF PORTLAND, MAINE, A CORPORATION OF MAINE.

LOCK-STITCH SEWING-MACHINE.

2,216,035.

Specification of Letters Patent.

Patented Feb. 13, 1917.

Application filed July 10, 1913. Serial No 778,326.

To all whom it may concern:

Be it known that I, WILLIAM WILSON, a citizen of the United States, residing at Boston, in the county of Suffolk and State of Massachusetts, have invented certain new and useful Improvements in Lock-Stitch Sewing-Machines; and I do hereby declare the following to be a full, clear, and exact description of the invention, such as will enable others skilled in the art to which it appertains to make and use the same.

The present invention relates to lock stitch sewing machines, and more particularly to lock stitch sewing machines in which the loop of needle thread is cast about a stationary bobbin case by means of a rotary hook:

The object of the present invention is to provide the sewing machine with means for positively freeing the hook of the thread. The present invention, in one of its more limited aspects, relates to the combination of a rotary hook for casting a loop of thread around the bobbin case having a thread-receiving groove with an undercut recess in its side in which the thread is held by its tension, and a cast-off projection for lifting the thread out of this undercut recess.

In the drawings, which illustrate the preferred embodiment of the invention, Figure 1 is a plan view; Fig. 2 is a section taken along the line 2—2 of Fig. 1; Fig. 3 is a section taken along the line 3—3 of Fig. 1; and Fig. 4 is a fragmentary section taken in the same section plane as Fig. 2 showing the undercut portion of the hook without the thread.

In the illustrated embodiment of the invention, a loop of thread is drawn down by a vertically reciprocating barbed needle and is cast about the bobbin case 1 by means of a rotary hook, indicated generally by reference numeral 2, which rotates in a plane inclined at about 60 degrees to the direction of reciprocation of the needle. The hook comprises an annular body portion 3 and an inwardly directed thread-engaging beak 4 which enters the loop of thread drawn down by the needle and takes it from the barb 5 of the needle. The annular body portion 3 of the hook has at its lower end an inwardly projecting flange 5 which is engaged in an annular race-way formed between the body of the hook supporting frame 6 and a plate 7 secured to the top of the supporting frame.

The hook makes three revolutions to each reciprocation of the needle and is continuously rotated in timed relation therewith by means of a bevel gear wheel 10 which meshes with bevel gear teeth 11 cut in the periphery of the annular body 3. The barbed needle (not shown) passes upwardly through the passage 12 in the hook supporting frame 6 and plate 7, through the annular body of the hook and through the cut-away portion 13 of the bobbin case, and draws down through the throat plate of the machine a loop of thread which is entered by the beak 4. The loop of needle thread taken from the needle by the beak 4 slips into the thread-receiving groove 8 of the hook which acts to spread the loop of needle thread and carry it about the bobbin case 1. The hook supporting frame 6 is a frame substantially U-shaped in outline having two legs 15 and 16 in the ends of which are formed co-axial bearings 17 and 18 by means of which the hook supporting frame 6 is hinged to the machine. The hook support 6 is given a limited oscillation about the bearings 17 and 18 once for every reciprocation of the needle so that the beak 4 will pass to the left, as viewed in Figs. 1 and 2, of the needle and thus clear the needle during the two idle rotations of the hook. The gear wheel 10 is mounted to rotate on the shaft 20, which is rigidly mounted in the supporting frame 6, and held in place by means of the nut 21. At the end of the hub 22 of the gear wheel 10 is formed a universal joint 23 through which power is transmitted from a gear wheel 24 mounted to rotate upon a shaft 25 fixed to the machine frame. The bobbin case 1 is discoidal in outline and is rotatably mounted within the annular body 3 of the hook upon an annular plate 30 which is rigidly secured to the top of the hook body 3 and which lies in a plane normal to the axis of rotation of the hook and the inner periphery of which is received in a race-way 31 cut around the periphery of the bobbin case 1. The bobbin case has in its upper end face a cup-shaped bobbin-receiving recess 32 in which is a central post 33 upon which is rotatably mounted a bobbin 34. The bobbin 34 is removably held in place by means of a spring-pressed latch 35. The bobbin case 1 is prevented from rotating with the supporting hook 2 by means of detent pins 40 and 41 which engage circular detent-receiving

recesses in the top of the bobbin case. The 5 detent pins 40 and 41 are mounted upon the ends of two bell crank levers 46 and 47 which are co-axially fulcrumed to oscillate about a shaft 50 mounted on the hook supporting frame 6. The bell crank levers 46 and 47 are provided at their lower ends with cam rolls which run in a cam groove 60 and act to advance and withdraw the detent pins 10 40 and 41 in timed relation with the rotation of the hook in order that the loop of thread may be permitted to pass over the upper face of the bobbin case. The detent pins 40 and 41 are provided with thread guards 70 and 15 71 to prevent the thread from catching on them. The above described parts have substantially the same construction and mode of operation as those illustrated and described in the co-pending application of 20 Laurence E. Topham, Ser. No. 754,214, filed March 14, 1913, to which reference is had by permission. The mechanism herein described is a part of the lock-stitch wax-thread harness sewing machine, known to 25 the trade as the "Campbell Cyclone" stitcher. The thread-receiving groove 8 of the hook extends in a direction across the plane of rotation of the hook, or in other words, in a direction generally lengthwise of the 30 bobbin case 1. The loop of needle thread is expanded by this groove lengthwise of the bobbin case so that the lower leg of the loop extends from the groove just below the lower end face of the bobbin case and the upper 35 leg of the loop extends from the groove just above the upper end face of the bobbin case. The groove 8 is longitudinally convex, as shown in Fig. 3, at its lower end extending at approximately right angles to the plane 40 of rotation of the hook and at its upper end terminating in a portion 80 which is but slightly inclined to the plane of the hook. The upper or inclined portion 80 of the thread-receiving groove has in its inner wall 45 an undercut recess 81 in which the thread is drawn and is securely held by its own tension as the hook carries the loop around the bobbin case. The thread is positively lifted out of the undercut portion of the groove 50 by means of the edge of the upper end face on a cast-off projection 82 of the bobbin case. This cast-off projection 82 is a riser or cam beginning at a point 83 diametrically across the bobbin case from the needle, rising 55 gradually beyond this point (in the direction of the movement of the thread around the bobbin case), and again merging with the end face of the bobbin case at a point 84. The operation of the machine is as follows:—

The inwardly directed beak 4 takes the loop of thread from the needle barb. As the hook begins to carry the loop of thread around the bobbin case, the thread slips into 65 the groove 8 which expands or spreads the

loop lengthwise of the bobbin case. As the thread-receiving groove 8 gets to the side of the bobbin case opposite the needle or throat plate of the machine, the tension of the thread draws it firmly into the undercut recess 81, so that there is no tendency for the sidewise pull of the thread, when the parts are in the positions shown in Fig. 1, to cause the loop to be pulled or jump out of the thread-receiving groove 8. In fact, the 70 tighter the thread, the more firmly it is held in the undercut recess 81. The thread is thus securely held by the hook until the hook has performed its function in drawing out the loop to its greatest distention and carrying it across the side of the bobbin case 80 which is diametrically opposite the throat plate or needle. After the loop has passed its position of greatest distention (approximately shown in Fig. 1) it must be freed 85 from the hook so as to be drawn in by the take-up of the machine. In order to free the hook of the thread at the proper time, the cast-off projection 82 is placed where it will operate to lift the thread out of the 90 thread-receiving groove 8 shortly after the loop has passed its position of greatest distention. As shown in Fig. 3 more particularly, the thread which lies in the inclined portion 83 of the thread-receiving groove 95 hook is lifted or pushed in a direction approximately normal to the plane of rotation of the hook by means of the cast-off projection 82. As soon as the thread has been lifted by the cast-off projection 82 out of the 100 undercut inclined portion 83 of the groove, it can be readily pulled from the groove by the take-up. The undercut recess 81 and the cast-off projection 82 coöperate with each other to positively control the thread during 105 the operation of casting the loop around the bobbin case, for, as above pointed out, the thread is snugly and securely held by its own tension in the undercut recess 81 until it is lifted from it by the cast-off projection 110 82. The cast-off projection 82 operates to free the hook of the thread at the same point during each cycle of the stitch forming operations, so that uniformity in the stitches is secured.

While the preferred invention has been described in connection with its preferred embodiment, it is to be understood that the present invention is not limited to the illustrated embodiment, but may be embodied in 120 other constructions of sewing machines within the scope of the invention as set forth in the following claims.

I claim—

1. A lock stitch sewing machine having, 125 in combination, a bobbin case, a rotary hook for casting a loop of needle thread about the bobbin case, and means engaging the thread in proximity to the hook and moving the thread substantially normal to the plane of 130

- rotation of the hook for lifting the thread out of the hook after the loop has passed its position of maximum distention in traveling about the bobbin case.
5. 2. A lock stitch sewing machine having, in combination, a bobbin case, a rotary hook for casting a loop of needle thread about the bobbin case, and a stationary cast-off projection engaging the thread in proximity to the hook for lifting the thread out of the hook after the loop has passed its position of maximum distention in traveling about the bobbin case.
10. 3. A lock stitch sewing machine having, in combination, a stationary bobbin case, a rotary hook for casting a loop of needle thread about the bobbin case, said bobbin case having a cast-off projection for lifting the thread out of the hook after the loop has passed its position of maximum distention in traveling about the bobbin case.
15. 4. A lock stitch sewing machine having, in combination, a bobbin case, a rotary hook for casting a loop of thread about the bobbin case having a thread-receiving groove with an undercut recess in one of its sides in which the thread is held as the loop is carried around the bobbin case by the hook, and means for lifting the thread out of the undercut recess after the loop has passed its position of maximum distention in traveling about the bobbin case.
20. 5. A lock stitch sewing machine having, in combination, a stationary bobbin case, a rotary hook for casting a loop of needle thread about the bobbin case having a cast-off projection for lifting the thread out of the undercut inclined portion of the groove terminating at one end in a portion inclined to the plane of rotation of the hook, said bobbin case having a cast-off projection for moving the thread substantially normal to the plane of rotation of the hook to lift it out of the inclined portion of the groove after the loop has passed its position of maximum distention in traveling about the bobbin case.
25. 6. A lock stitch sewing machine having, in combination, a stationary bobbin case, a rotary hook for spreading a loop of needle thread and casting it about the bobbin case having a thread-receiving groove extending in a direction across the plane of rotation of the hook and terminating at one end in a portion inclined to the plane of rotation of the hook, said inclined portion having an undercut recess in which the thread is held by its own tension as the loop is carried around the bobbin case, said bobbin case having a cast-off projection for lifting the thread out of the under-cut inclined portion of the groove.
30. 7. A lock stitch sewing machine having, in combination, a stationary discoidal bobbin case, a rotary hook having an annular body surrounding and supporting the bobbin case and having a thread-receiving groove for spreading a loop of needle thread lengthwise of the bobbin case and casting it about the bobbin case, said groove extending in a direction generally lengthwise of the bobbin case and terminating at one end in a portion inclined to the plane of rotation of the hook, said inclined portion having an undercut recess in one of the sides of the groove in which the thread is held by its own tension as the loop is carried about the bobbin case by the hook, said bobbin case having a cast-off projection for engaging the thread and lifting it out of the undercut inclined portion of the groove after the loop has passed its position of maximum distention in traveling about the bobbin case.
35. 8. A lock stitch sewing machine having, in combination, a stationary discoidal bobbin case, a rotary hook having an annular body surrounding and supporting the bobbin case and having a thread-receiving groove for spreading a loop of needle thread lengthwise of the bobbin case and casting it about the bobbin case, said groove extending in a direction generally lengthwise of the bobbin case and terminating at one end in a portion inclined to the plane of rotation of the hook, said inclined portion having an undercut recess in one of the sides of the groove in which the thread is held by its own tension as the loop is carried about the bobbin case by the hook, said bobbin case having a cast-off projection for lifting the thread out of the undercut inclined portion of the groove after the loop has passed its position of maximum distention in traveling about the bobbin case.
40. 9. A lock stitch sewing machine having, in combination, a stationary bobbin case, a rotary hook for casting a loop of needle thread about the bobbin case having a cast-off projection for lifting the thread out of the undercut recess after the loop has passed its position of maximum distention in traveling about the bobbin case.
45. 10. A lock stitch sewing machine having, in combination, a stationary bobbin case, a rotary hook for casting a loop of needle thread about the bobbin case having a
